UNITED STATES PATENT OFFICE.

HAROLD R. JOHNSON, OF CRANSTON, RHODE ISLAND.

PENCIL.

1,422,984.

Specification of Letters Patent.

Patented July 18, 1922.

Application filed June 3, 1921. Serial No. 474,682.

To all whom it may concern:

Be it known that I, HAROLD R. JOHNSON, a citizen of the United States, residing at Cranston, in the county of Providence and State of Rhode Island, have invented certain new and useful Improvements in Pencils, of which the following is a specification.

My invention relates to magazine pencils wherein the lead is propelled and retracted.

10 The essential objects of my invention are to enable the entire length of the lead to be utilized; to facilitate assemblage of the parts and prevent cramping the same; to enable the use of a short screw and a sensitive action and control of the lead shaft. Other advantages will be apparent from an examination of the following specification.

To the above and kindred ends my invention consists in such parts and in such combinations of parts as fall within the scope of the appended claims.

In the accompanying drawings which form a part of this specification,

25 Figure 1 is a side elevation of my novel pencil,

Figures 2 and 3, vertical central sections of the same, showing the lead carrying parts in side elevation, and in two different positions of propulsion,

30 Figure 4, a section taken on line 4—4 of Figure 3 but with the lead carrying parts in the third position,

Figure 5, a longitudinal section of the shell,

35 Figure 6 a perspective view of the guide tube and ferrule,

Figure 7, a side elevation of the screw,

Figures 8, 9, and 10, perspective views respectively of the carrier controller, the 40 plunger, and the lead carrier, and

Figure 11, a section on line 11—11 of Figure 6.

Like reference characters indicate like parts throughout the views.

45 My pencil comprises a shell 13 provided with a body portion 14 and an integral conical tip or point tube 15. In the shell is rotatably mounted a helical tubular screw or sheath 17 provided with the helical groove or slot 18 and terminating at its lower end with a horizontal curved point 19. The head portion of the screw member comprises a ferrule 21 provided with an external annular shoulder 22 and terminating in a 50 milled knob 24. The upper coil of the screw

is fast by spring pressure to the interior face of the ferrule. An inturned shoulder or flange 28 on the upper end of the shell 13 overlaps the shoulder 22, whereby the screw is rotatably mounted in the shell.

Concentric of the shell and within the screw is a tubular guide 30 provided throughout its length with a longitudinal slot 31. A conical spring ferrule 32 provided with an opening 33 in its lower portion and longitudinal slots 34 extending from points near the opening to form resilient segments 35 is rigidly mounted on the guide, and a projection 36 on the bottom of the ferrule extending into the slot 31 of the guide prevents rotation of the ferrule on the guide, and the segments 35 snugly and rigidly engage the casing tip 15. This ferrule rigidly maintains the guide in position. Slidably mounted on the guide 30 is a 65 cylindrical controller 37 for the lead carrier comprising a longitudinally cut away intermediate portion 38 forming a longitudinal slot 39, and longitudinally split upper and lower sleeve portions 40 and 41 respectively, 70 the former being provided with a hole 42.

The lead carrier consists of the usual split tube 44 for enclosing the lead 47, having upon its upper end a lug 46. The carrier is 75 slidable in the guide 30, and the lug 46 slides in and projects through the slot 31 of the guide and 39 of the carrier controller. The sleeve portions of the controller form 80 stops which limit the reciprocal travel of the lead carrier lug 46.

Slidable in the carrier is a long plunger rod 48 with a lateral end finger 49 above the carrier and projecting through the slot 30 and the hole 42.

In full retracted position, as shown in 95 Figure 2, the finger 49 and lug 46 extend into the helical groove 18 of the screw, and travel downwardly therein in unison as the screw is manually rotated by means of the knob 24, the lead 47 being exposed for use. 100 As the screw revolution is continued the controller 37 with the lead 47 continues to slide downwardly, with the elements 49 and 46 traveling in the groove 18 until the lug 46 reaches a point below the point 19, as 105 shown in Figure 3, whereupon the lead carrier 44 discontinues its descent and the last portion of the lead 47 is exposed for use. If, however, it is desired to eject the lead 47 from the casing, the rotation of the screw is 110

continued and operates solely on the controller 37 and the finger 49 until the controller strikes the ferrule 32 and the plunger projects beyond the tip 15, as shown in Figure 4. By means of the controller, therefore, not only is it possible to thoroughly expel the lead and utilize the entire length of lead, but this end can be attained by use of a comparatively short screw, which is important in that it makes it possible to include all the advantages of this type of pencil in a short body. To retract the parts to original position the described operations are reversed by rotating the screw in the opposite direction. This elevates the plunger, and as the controller rises the sleeve portion 41 finally presses against the lower edge of the lug 46 and raises it sufficiently for the screw point 19 in its rotation to also pass beneath the lug and impel it upwardly in the groove 18 in unison with the plunger finger.

I claim:

1. In a pencil of the character described, a shell, a tubular guide rigidly supported in the shell concentrically thereof and provided with a slot, a screw rotatably supported in the shell surrounding a portion of the guide, a tubular controller slidably mounted on the guide provided intermediate its length with a longitudinal slot and with a hole, a lead carrier slidably mounted in the guide, a lug on the carrier extending through the slots and into the screw, a plunger slidable in the carrier, and a finger on the plunger extending through the first slot, and hole, and into the screw.

2. In a pencil of the character described, a shell comprising a body and a tapering tip, a tubular guide provided with a slot, a ferrule fast to the guide comprising tapering resilient segments engaging the tip, a projection on the ferrule extending into the slot, a screw rotatably supported in the shell, a carrier in the guide, and a lug on the carrier engaging the screw.

3. In a pencil of the character described, a shell comprising a body, a tapering tip integral therewith at one end, and a flange at the other end, a ferrule extended within the end of the shell and provided with an annular shoulder rotatably engaged by the flange, a head on the ferrule, a screw fast in the ferrule, a tubular guide supported in the shell concentrically of the screw and provided with a longitudinal slot, a lead carrier slidably mounted in the guide, and

a lug on the carrier extending through the slot and engaging the screw.

4. In a pencil of the character described, a shell, a tubular guide rigidly supported in said shell and having a slot, a screw rotatably supported in the shell around the guide, a controller around the guide and within the screw, and a lead carrier slidably within the guide and governed for a portion of its travel by said controller.

5. In a pencil of the character described, a shell, a tubular guide rigidly supported in said shell and having a slot, a screw rotatably supported in the shell around the guide, a controller around the guide and within the screw, a lead carrier slidably within the guide and governed for a portion of its travel by said controller, and a plunger rod operable to move the lead after said controller has discontinued its travel.

6. In a pencil of the character described, a shell, a slotted tubular guide, a screw rotatably supported in the shell around the guide, a tubular controller around the guide and within the screw, a lead carrier in said guide and having a finger working in the slot of the guide, and a plunger rod in the lead carrier working in said slot, said lead carrier and plunger rod being controlled in their movements by said controller and screw.

7. In a pencil of the character described, a shell, a slotted tubular guide, a screw rotatably supported in the shell, a lead carrier, a plunger rod, each with a projection working in the slot of the guide, and a tubular controller having a slot through which said projections extend, said controller also having shoulders for cooperation with the projection on the lead carrier.

8. In a pencil of the character described, a shell, a slotted tubular guide, a screw rotatably supported in the shell, a lead carrier, a plunger rod, each with a projection working in the slot of the guide, and a tubular controller having a slot through which said projections extend, said controller also having shoulders for cooperation with the projection on the lead carrier, the projection on the said plunger rod cooperating with the screw for the entire travel thereof, and the projection of the lead carrier being disengageable from operative relation with said screw after a portion of its travel.

In testimony whereof I have affixed my signature.

HAROLD R. JOHNSON.
